UNITED STATES PATENT OFFICE.

AUGUSTUS E. SCHNOSE, OF DELL RAPIDS, SOUTH DAKOTA.

APPARATUS FOR STRETCHING WOVEN-WIRE FENCES, &c.

1,116,633.

Specification of Letters Patent.

Patented Nov. 10, 1914.

Application filed May 7, 1914. Serial No. 837,028.

To all whom it may concern:

Be it known that I, AUGUSTUS E. SCHNOSE, a citizen of the United States, residing at Dell Rapids, in the county of Minnehaha 5 and State of South Dakota, have invented certain new and useful Improvements in Apparatus for Stretching Woven-Wire Fences, &c.; and I do hereby declare the following to be a full, clear, and exact description of the invention, such as will enable others skilled in the art to which it appertains to make and use the same, reference being had to the accompanying drawings, and to the letters and figures of reference 10 marked thereon, which form a part of this specification.

This invention relates to new and useful improvements in apparatus for stretching woven wire fences, etc., and comprises a simple and efficient device of this nature having various details of construction, combinations and arrangements of parts which will be hereinafter fully described, shown in the accompanying drawings and then specifically defined in the appended claim.

My invention is illustrated in the accompanying drawings, in which:

Figure 1 is an elevation of a wire stretcher made in accordance with my invention. 30 Fig. 2 is a top plan view, and Fig. 3 is a view partially in section.

Reference now being had to the details of the drawings by letter, A designates the end post of the apparatus comprising two laterally extending beams B and C connected together by means of an upright piece D. At the ends of the beams B and C are the pointed plates E held by means of bolts or otherwise to said beams and projecting beyond 35 the ends thereof and are adapted to engage an end post F about which the wires are to be stretched and fastened. A rotatable shaft H is journaled in suitable bearings in the opposite beams B and C and about which a 40 rope or cable I is adapted to wind, said rope or cable passing about the pulleys N and O, the former pulley N being attached to a wire or rope O' which passes about the clamping members P between which the fabric is 45 adapted to be clamped, the two clamping members being held in clamping relation 50 by means of the screws Q. The pulley O is

mounted upon a hook M and the end of the rope is fastened to a hook J.

A ratchet wheel R is fixed to the rotatable 55 shaft H, and L designates a bar having its ends L' bent at an angle forming handles, said bar having an angular-outlined opening designed to receive the upper angular end H' of the shaft H, the corners of said angular portion of the shaft being provided with broken threads H² and upon which the nuts S and S' are mounted, between which nuts a ratchet wheel T is mounted. A pawl W is pivotally mounted upon the upper surface 60 of the beam C and is adapted to be thrown into engagement with the ratchet disk to prevent the shaft from rotating in one direction, said pawl being loosely mounted and adapted to be swung in opposite direction 65 out of engagement with the ratchet disk if desired to allow the shaft to turn freely in either direction. Guy wires, designated by letter V, are fastened to the beam C and their rear ends secured to any suitable anchorage.

In operation, the parts are adjusted as shown. The wire fabric to be stretched is engaged by the two members P and, by turning the shaft through the medium of 70 the handle L, the rope made to wind up upon the shaft, thus drawing the wire fabric clamped by the members into a taut relation about the post, as will be readily understood.

What I claim to be new is:

A wire stretching apparatus comprising a frame with a supporting post at one end and laterally extending beams therefrom, one disposed at an inclination and the other 90 at right angles to the supporting post, spur plates secured to the free ends of said beams for engagement with a post about which a wire is to be stretched, a rotatable reel shaft journaled in apertures in said beams, a wire 95 clamping member adapted to move in contact with corresponding faces of said beams, a cable secured at one end to said post and winding about said reel shaft, pulleys secured one to the post and one to said wire 100 clamping member and about which pulleys a cable passes, the latter being adapted to draw the clamping member against the faces of the beams to cause a wire to be drawn

taut, a ratchet wheel fitted to the upper threaded end of the reel shaft, a pawl pivotally mounted upon said inclined beam and engaging the ratchet wheel, and a turning bar having a threaded aperture and engaging threads formed at the upper end of the shaft.

In testimony whereof I hereunto affix my signature in presence of two witnesses.

AUGUSTUS E. SCHNOSE.

Witnesses:

O. H. SMITH,
N. C. KLEIN.
